UNITED STATES PATENT OFFICE.

EMILIO R. SALAZAR, OF HABANA, CUBA.

AUTOMATIC TRAIN STOP.

Application filed March 28, 1919. Serial No. 285,831.

To all whom it may concern:

Be it known that I, EMILIO R. SALAZAR, a citizen of Cuba, residing at Habana, in the Province of Habana and Republic of Cuba, have invented new and useful Improvements in Automatic Train Stops, of which the following is a specification.

My present invention pertains to automatic train stops.

10 One of the objects of the invention is the provision of an automatic train stop equipment adapted to work satisfactorily in the winter in a location where it is exposed to the elements.

15 Another object of the invention is the provision of simple, reliable and easily installed electro-mechanical means for bringing about a stop of a locomotive or train when a condition of danger is encountered.

20 Other objects and practical advantages of the invention will be fully understood from the following description and claims when the same are read in connection with the drawings, accompanying and forming part 25 of this specification, in which:

Figure 1 is a plan view, partly diagrammatic, illustrative of the track equipment, constructed in accordance with my invention.

30 Figure 2 is a detail view showing the relation of the third rail to the running rails of the railway.

Figure 3 is an enlarged detail view, showing the installation of a portion of my invention in a locomotive.

35 Figure 4 is an enlarged longitudinal vertical section illustrating the explosion chamber comprised in the locomotive equipment, and the appurtenances of said chamber.

40 Figure 5 is an enlarged detail section of the valve connected with said explosion chamber and designed following an explosion in said chamber to bleed air from a fluid pressure brake system with a view to 45 bringing a train to a gradual stop.

Figures 6 and 7 are detailed views of the equipment constructed in accordance with my invention and carried by the forward truck of the locomotive.

50 Similar numerals designate corresponding parts in Figures 1, 2, 6 and 7, to which reference will first be had.

By particular reference to Figure 1, it will be seen that the running rails 1 of the railway are arranged in the usual manner on sleepers 2, and that the railway is divided

into sections or blocks by the use of insulation 3 in the rails or between the meeting ends of adjoining rails at suitable intervals. It will also be observed that the track equipment comprises a battery 4 connected through wires 5 with the rails 1, an automatic semaphore block signal 6, a relay 7, a signal battery 8, a third rail 9, a wire connection 10 between one of the rails 1 and the relay 7, a wire connection 10^a between the other rail 1 and the relay and an electrical connection from one side of the signal battery 8 through the conductor 11, armature 12, contact 13 and conductor 14 to the contact rail 9.

When a train is in the block shown at the right of Figure 1 while a train is in the preceding block, current will pass from the rail 9 through the locomotive connections to the insulated section of rail 27^a and through the conductor 28^a to the other side of the battery 8. This will bring about the stoppage of the locomotive in the block at the right of Figure 1 with its contact roller 16 in engagement with 9 in the manner and by my improved means complementary to the locomotive as hereinafter set forth.

The third rail 9 is approximately thirty-three feet in length and has its ends 9^a bent downwardly, Figure 2. The top of the said third rail is about two and a half inches higher than the tops of the running rails, and the third rail is preferably superimposed on small blocks or bars 9^b.

In my novel third rail 9 it is feasible to use the full voltage of the signal battery 8, inasmuch as the said third rail 9 is not in a position to short circuit the relay. Moreover, the current is not in the third rail 9 continuously as in the track circuit, but is only in said third rail when the semaphore arm is in the stop position—i. e., when a train bridges the gap between the third rail 9 and one track rail 1. In consequence,

when the semaphore arm is in the stop position, the desired condition of an electro-motive force of ten volts or more is brought into existence between the third rail 9 and one of the running rails 1. This manifestly is ample to heat the resistance 49, herein-after described, to incandescence.

It will be noted here that the provision of the third rail 9, in conjunction with the equipment described, obviates the necessity of employing movable trips along the trackway; which are objectionable because of their

tendency to fail to work properly in the winter season when they are subject to the influence of ice, sleet and snow.

I prefer, in practice, to fix the contact 5 wheel 16, Figures 6 and 7, to an axle 17, and to have the said axle revolve in a journal box 18, which is insulated from the supporting frame 19, as indicated at 20. I also prefer to have the said wheel 16 located to 10 run about two inches higher than the running rails 1, and to so proportion the supporting frame 19 that the same will impose part of the load of the truck on the wheel 16 in order to assure said wheel making a 15 good contact with the rail 9.

In the illustration of the locomotive, Figure 3, the throttle valve 21, the operating lever 22 and the connection complementary to said valve and lever are of the ordinary 20 well known construction, as is also the steam turret 23 and the dome 24 and dry pipe 25.

In furtherance of my invention, I provide in connection with the pipe 25, designed to 25 lead steam from the throttle valve 21 to the piston cylinders of the locomotive, a valve body 26, a seat 27 therefor, a support 27' for the stem 28 of the valve body, a casing 29 which snugly receives a portion 30 of body 26, and a spring 31 which operates to 30 turn the valve body 26 to and normally maintain the same in the position shown in Figure 3. I also employ the explosion chamber 30' shown in Figures 3 and 4, as well as the valve construction shown in Figures 3 35 and 5. When closed against the seat 27 by the means hereinafter described, the valve body 26 is designed to cut off the supply of steam to the pipe 25 and thereby stop the driving of the locomotive. As best shown 40 in Figure 4 the explosion chamber 30' communicates with a valve chamber 32, in which is arranged a spring actuated check valve 33, and the chamber 32 merges into a reducer 34 that is connected through a pipe 35 with the casing 29 at the opposite side of the valve body 26, with reference to the 45 pipe 25. Arranged, as shown in the explosion shell 30', is a chamber 40 containing an explosive charge 41; the said shell being 50 held in place by a composition body 42. The threaded aperture 43 in the wall of the chamber 30' receives a fuse plug 44, equipped with suitable insulation 45 and a binding post 46 for the electrical connection. A main electrode 47 from the binding 55 post 46 and a ground electrode 48 connected to the base of the plug 44 are preferably of copper and project through the composition body 42 and have between them a resistance 49 formed by preference of platinum wire. Manifestly the resistance may be of any appropriate material other than platinum without affecting my invention. The said resistance is disposed in the explosive charge 40, and from this it follows

that when the resistance is heated to incandescence by the passage therethrough of electrical current the explosive charge will be ignited and gas will be produced in the chamber 30'. The reducer 34 is provided as 70 shown in Figure 3, with a safety valve 50, which is designed to blow off at a much higher pressure than that of the boiler. The main electrode 47 and the binding post 46 of the ignition device are electrically connected with the bearing 18 of the contact wheel 16, and the electrode 48 of said device is grounded through the locomotive to the rail 1 at the right of Figure 1 in order to bring about the ignition of the explosive 75 charge 40 at the proper time and by the means before described. At this point, I would have it understood that the function of the valve 33 is to prevent steam from entering the explosion chamber 30' in the event of the steam leaking past the valve body 26. The valve construction, Figures 80 3 and 5, comprises a casing 60 that is connected through a pipe 61 with the explosion chamber 30' and through a pipe 62 with a reservoir 63 of a fluid pressure brake equipment. In addition to the said casing 60 the valve construction 31, as shown in Figure 5, comprises a piston 64, a valve 65, adapted to seat at 66, and a spring 67 adapted to normally hold the valve to its seat. Thus, under normal conditions, the valve 65 will rest in the position shown and prevent 85 passage of fluid under pressure from the reservoir 63 to the atmosphere. When, however, an explosion takes place in the chamber 30', the expanding gas will operate against the piston 64 and will unseat the valve 65 so as to allow air from the reservoir to bleed or escape slowly to the atmosphere through the aperture 68 in casing 60, and thereby bring about a gradual application 90 of the fluid pressure brakes. 100

Normally the armature 12 is held to the 105 electro-magnets 7 of the relay, said magnets being at that time energized by current from the track battery 4. When as shown 110 in Figure 1 the track battery 4 is short circuited by train indicated by 15 at the left of the insulation point 3, and the magnets 7 are deenergized, the armature 12 makes electrical connection with the terminal 12 causing voltage to be thrown into the third rail 9, and at the same time the semaphore 6 is moved by the ordinary well known 115 means or any other means to the stop position shown in Figure 1. The direction of travel is supposed to be toward the left on the track shown in Figure 1, and hence when a locomotive equipped with my improvements follows the train indicated by 15, and the contact wheel 16 of said locomotive contacts with the third rail 9, steam 120 will be cut off from the piston cylinders of the locomotive and the fluid pressure brakes 125 130

will be applied in the manner hereinafter set forth.

In the practical operation of the locomotive equipment portion of my improvement it will be observed that when the wheel 16 is in contact with the third rail 9, the resistance 49 in the explosive charge 41 will be heated to incandescence, and gas will be generated in the chamber 30. This gas will 10 compress the dead air in the pipe 35 and the valve 26 will be forced towards the left in Figure 3 and thereby cut off the supply of steam from the locomotive cylinders, and at the same time the valve construction best 15 shown in Figure 5 will be actuated to permit fluid under pressure to escape slowly from the reservoir 63 to the atmosphere and thereby bring about a slow and steady application of the fluid pressure brakes.

Having described my invention, what I claim and desire to secure by Letters Patent, is:—

1. The combination of a locomotive steam pipe, a cut-off valve complementary thereto, 25 an explosion chamber, a conduit intermediate said chamber and the casing of said cut-off valve, means in the explosion cham-

ber for holding an explosive charge, and means for igniting such charge to bring about movement of the cut-off valve to close 30 the pipe.

2. The combination of a locomotive steam pipe, a cut-off valve complementary thereto, an explosion chamber, a conduit intermediate said chamber and the casing of said cut-off valve, a check valve in said conduit, means in the explosion chamber for holding an explosive charge, and means for igniting such charge to bring about movement of the cut-off valve to close the pipe. 35

3. The combination of a locomotive steam pipe, a cut-off valve complementary thereto, an explosion chamber, a conduit intermediate said chamber and the casing of said cut-off valve, means in the explosion chamber for holding an explosive charge, a valve for exhausting fluid under pressure from a fluid pressure brake system, and a conduit connection between the explosion chamber and said valve to put the valve into operation 45 for said purpose incidental to an explosion in the chamber.

In testimony whereof I affix my signature.
EMILIO R. SALAZAR.
